UNITED STATES PATENT OFFICE.

GEORGE A. CARNEY, OF BOSTON, MASSACHUSETTS, ASSIGNOR OF ONE-HALF TO
GEORGE H. LITTLEFIELD, OF BOSTON, MASSACHUSETTS.

HANDCUFF.

1,017,955.

Specification of Letters Patent. Patented Feb. 20, 1912.

Application filed October 4, 1911. Serial No. 652,881.

To all whom it may concern:

Be it known that I, GEORGE A. CARNEY, of Boston, in the county of Suffolk and Commonwealth of Massachusetts, have invented a new and useful Improvement in Handcuffs, of which the following is a specification.

My invention relates more particularly to means for locking and unlocking the handcuff and it has been the special object of my invention to provide an automatic locking arm which need not be positively locked in order to keep it in place when the device is not in use, it being provided with means whereby it may be securely held in place when not in use and yet may be instantly and easily opened in order to admit the wrist.

My invention may be best understood by reference to the accompanying drawing, in which—

Figure 1 is a side view of the device, the locking arm being shown in operative position. Fig. 2 is an end view. Fig. 3 is a side view with the lower part of the casing cut away to show the interior of the mechanism.

Referring now more particularly to the drawing, 1 is a casing which is provided with an upwardly extending arm 2 which is divided so that the locking arm 3 may be mounted by the pivot 4 between its extremities.

5 is a key-hole in the casing. The locking arm 3 is provided with a serrated edge 6, adapted normally to engage the end of the arm 7 of the pawl 8 and prevent its withdrawal. The pawl 8 is actuated by the spring 9 to move upon the pivot 10. 11 is a hole in the case 1, through which passes a ring 12 attaching the handcuff to its mate. It will be seen that the spring 9 normally forces the pawl 8 upward, causing its arm 7 to contact with the stop 13, which prevents its further movement in that direction. The teeth of the serrated edge 6 are such that when in operative contact with the end of the arm 7 of the pawl 8 the outward movement of the locking arm 3 is prevented by the contact of the arm 7 with the stop 13. By the insertion of a key in the key-hole 5, however, the pawl 8 may be actuated against the force of the spring 9, thus swinging the arm 7 out of contact with the serrated edge 6 of the locking arm 3 and

permitting the locking arm 3 to be withdrawn into an open position. It is apparent, however, since the serrated edge 6 of the locking arm 3 may be always moved inward across the top of the arm 7 until it 60 passes through the divided arm 2 of the casing 1, as shown by the dotted lines in Fig. 3, the handcuff may thus be readily opened at any time when not on the wrist of a wearer by a continuation of the movement of the locking arm 3 so that it swings around a full circle.

It is apparent that my handcuffs are compact, simple, easily operable and adjustable to the size of the wrists of the wearer and 70 have the further advantage that they will not fly open when carried in the pocket, thus causing inconvenience to the person carrying them, as is the case with the ordinary handcuff, which must be kept locked to render it compact and to avoid inconvenience when carried in the pocket. To be able to dispense with a key in opening my handcuffs when they are not attached to the wrists of a wearer and yet are in a measure 80 locked is obviously of great advantage.

It is evident that any desirably complicated key-operated means for actuating the pawl 8 may be used in connection with my device.

Having thus fully described my invention what I claim is—

1. In a handcuff the combination of a fixed part, a locking means in said fixed part and a locking arm pivotally mounted on said fixed part in a manner whereby it may be revolved so as to be brought into or out of operative relation with said locking means by a continuous motion.

2. In a handcuff the combination of a fixed part, a locking arm pivotally mounted on said fixed part in a manner whereby it may be revolved and a locking means normally operating to check the revolution of said locking arm in one direction while allowing it to move freely in another direction.

3. In a handcuff the combination of a casing, an upwardly extending arm on said casing, a locking arm, means for pivotally mounting said locking arm on said upwardly extending arm on said casing in a manner whereby said locking arm may be revolved and means in said casing for locking said locking arm.

4. In a handcuff a locking arm provided with a serrated edge, means for pivotally mounting said locking arm in a manner whereby it may be revolved, a pawl adapted to engage the serrated edge of said locking arm and intermesh therewith, a stop to limit the movement of said pawl in one direction, thereby preventing its movement out of mesh with said serrated edge of said locking arm and a spring adapted to actu-

ate said pawl into operative relation with said member provided with a serrated edge.

In witness whereof I have hereunto set my name in the presence of two subscribing witnesses.

GEORGE A. CARNEY.
